INVENTOR

BY *Victor J. Evans*

ATTORNEY

UNITED STATES PATENT OFFICE.

HENRY CLAUS, OF EAST NORTHPORT, NEW YORK

TOY.

Application filed July 17, 1925. Serial No. 44,305.

To all whom it may concern:

Be it known that I, HENRY CLAUS, a citizen of the United States, residing at East Northport, in the county of Suffolk, Long Island, and State of New York, have invented new and useful Improvements in Toys, of which the following is a specification.

This invention relates to improvements in toys, the general object being the contemplation of a hollow base to be placed upon a hot air register and having positioned within its lower portion a vertically disposed shaft having a plurality of propeller blades thereon which will be caused to be rotated by the heat waves thus emitted from the register box and the said shaft including upon its upper portion a plurality of objects to be carried around upon the successive rotations of the said shaft.

Another object of my invention is the provision of manually operated means included upon the upper portion of the vertically disposed rotatable shaft in order that a user may manually propel the said toy when no air is thus emitted from the register box.

With the above and other objects in view the invention further includes the following novel features and details of construction, to be hereinafter more fully described, illustrated in the accompanying drawings and pointed out in the appended claim.

In the drawings:—

Figure 1 is a top plan view of my invention.

Figure 2 is a bottom plan view thereof.

Figure 3 is a vertical sectional view.

Figure 4 is a longitudinal sectional view taken through one of the objects supported upon the upper portion of the shaft.

Figure 5 is a vertical sectional view taken on line 5—5 of Figure 4.

Referring to the drawings in detail, where-in like characters of reference denote corresponding parts, the reference character 10 indicates a frusto-conical shaped supporting base, its upper and lower sides open, the purpose of which will be presently apparent.

Secured to and supported upon the inner ends and upper sides of radially disposed supporting arms 11 which are secured to the inner sides and adjacent the upper periphery of the frusto-conical supporting base 10 is a disk 12 having a substantially elongated frusto-conical tower 13 extending cen-

trally thereabove. A transversely disposed channel bar 14 is arranged within the inner sides of the frusto-conical supporting base 10 and having positioned centrally thereof and held between the channel portions defined thereby, a cup bearing 15 for journaling the lower end of the vertically disposed shaft 16 therein being arranged within the tower 13 and disk 12. A bearing sleeve 17 is arranged upon the upper portion of the tower 13 in order that the said shaft 16 will be held in its vertically disposed position.

Fixed to the upper free end of the vertically disposed shaft 16 is a triangular plate 18 terminating at its respective corners in downwardly extending apertured ears 19 for the reception of looped portions 20 formed intermediate the lengths of arms 21, the purpose of which will be presently apparent.

Referring especially to Figures 4 and 5 of the drawings wherein the objects, to be suspended by the arms 21, are in the form of miniature airplanes composed of bodies 22 having their lower edges terminating in inwardly disposed tabs 23 and extending through plates 24 terminating at their respective ends with upwardly and outwardly extending wings 25. Fitted within the rear portion of the bodies 22 are plates 26 terminating at their respective inner and outer end portions with figure heads 27 and tails 28, the former extending upwardly in the form of keys 30 stamped from the plates 26 extend upwardly within openings provided in the top of the bodies 22 and when being twisted upon themselves will rigidly hold the plates 26 within the bodies 22 and the figure heads 27 will be held upwardly and above the bodies 22 an appreciable distance.

As clearly illustrated in Figure 4 of the drawings the lower free end portion of the arms 21 are substantially offset, as illustrated as at 31 and 32 respectively; the said portions 31 extending within an opening provided in the rear portion of the bodies 22 in order to support this end of the airplane, as illustrated, while the forward offset end portion 32 extends downwardly and within the bodies 22 and outwardly through the front thereof and supporting thereon propeller blades 33 in order that the miniature appearance of an airplane in flight is simulated. In order to provide means upon the vertically disposed shaft 16 and the triangu-

- lar plate 18 for manually operating the said vertically disposed shaft 16 and in operating the said miniature airplanes, I provide a knurled nut 34 upon the upper free end 5 of the vertically disposed shaft 16 which may be grasped by the thumb and index finger of an operator in rotating the said shaft 16 while the plate 18 includes a plurality of spaced depressed portions 35 with- 10 in its upper side and within which the finger tips of an operator may be placed and when twisted therein will impart the necessary momentum to the vertically disposed shaft 16 to swing the said airplanes.
- 15 A cardinal object of this invention was to place the same upon a register box leading from a hot air furnace, preferably upon a flat surface of floor, in order that the heat waves thus emitted from the register box 20 may be employed in supplying the source of momentum for the said toy and in order to accomplish this result and to attain the maximum efficiency thereby, I provide a plurality of radially disposed fan blades 36 25 which are secured centrally to the lower portion of the vertically disposed shaft 16 within the frusto-conical base 10 and immediately above the cup bearing 15 whereby the said heat waves thus emitted from the register box when the said base 10 has been placed thereover, will be caused to rotate owing to the fit of the fan blades 36 which will deflect the said heat waves upwardly through the top of the base 10 and which toy will 30 35 also indicate the velocity of the heat waves thus emitted from the register box owing to the speed thus attained and shown by the miniature airplanes thus carried by the supporting arms 21.
- 40 It is thus to be noted from the foregoing

description and accompanying drawings that this invention provides an exceedingly useful and attractive toy which may be used simultaneously as a means for indicating the velocity of heat waves thus emitted from a register box and yet form a pleasing object to the eye of a child.

The invention is susceptible of various changes in its form, proportions and minor details of construction, and the right is here- 45 50 reserved to make such changes as properly fall within the scope of the appended claim.

Having thus described my invention what is claimed is:

A toy of the character described comprising a hollow base, a beam mounted within the base and including a centrally disposed cup bearing intermediate its length and upon its upper side, a disk supported upon the upper portion of the base, a tower extending vertically and centrally above and connected to the disk a vertically disposed shaft extending within the disk and having its lower free end journaled within the cup bearing carried by the beam, a triangular 55 plate carried by the upper free end of the vertically disposed shaft and having its respective corners in downwardly disposed apertured ears, supporting arms formed from lengths of wire and forming looped 60 portions intermediate their length and pivotally secured within the apertured ears, a plurality of radially disposed fan blades fixed to the vertically disposed shaft within the base, and objects in the form of miniature airplanes suspended and carried by the lower free ends of the supporting arms.

In testimony whereof I affix my signature.

HENRY CLAUS.
